NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed April 21, 1926. Serial No. 103,419.

My invention relates to a lock and particularly to one embodying an improved shut out means.

It is the principal object of the invention 5 to provide a lock with improved shut out means for preventing a person supplied only with a special key from retracting the locking bolt and latch-bolt, but permitting the special key to be employed to retract the 10 latch-bolt when the locking bolt is retracted.

In the drawings which show, for illustrative purposes only, a preferred form of the invention—

Fig. 1 is a side view of a lock illustrating 15 the invention, the cover plate being removed to show interior construction;

Fig. 2 is a fragmentary view similar to Fig. 1 but illustrating parts in different positions;

Fig. 3 is a rear view of a locking bolt 20 and tumbler shown in Figs. 1 and 2;

Fig. 4 is an edge view of the locking bolt shown in Fig. 3.

In said drawings 5 indicates a lock case, 25 and 6 the face-plate to be attached to the edge of a door. A locking bolt 7 may be slidably guided through an opening in the face-plate, as indicated at 8, and the rear end of the locking bolt may be supported by 30 means of a link 9 pivoted to the case at 10, and by means of a loose connection pivoted to the pin 11 carried by the locking bolt. The locking bolt 7, at the rear side, carries 35 a tumbler 12 pivoted thereto at 13, and pressed into the position shown in the drawings by means of a spring 14. The tumbler may carry a projection 15 to engage in front of and in rear of a stump 16 on the inside of the lock case.

40 17 indicates a cylinder lock of a usual form, the rotatable plug of which carries at the inner end, a roll-back 18. The roll-back is formed so as to slidably hold a finger or plate 19, which is normally spring pressed 45 inwardly into the position shown in Fig. 1. By means of a long key, which may be referred to as a maid's key, the finger-plate 19 may be extended or projected outwardly into the position shown in Fig. 2 for a purpose 50 to be later described. A similar cylinder lock and roll-back is more fully described in Voight Patent, No. 1,099,105, dated June 2, 1914. The cylinder lock is so positioned that the roll-back may be ro-

tated as by means of a short key (plate 19 55 not being projected by such short key) to depress the tumbler 12 from the position shown in Fig. 1 so as to clear the lug 15 from the stump 16, and further rotation of the plug and roll-back will project the locking bolt 60 7 until the lug 15 engages the opposite side of the stump 16 to hold the locking bolt in projected position. With the finger 19 still in retracted position, the roll-back may be rotated in the opposite direction so as to depress the tumbler 12 and retract the locking bolt 7.

20 indicates a latch-bolt normally spring pressed outwardly as by means of a spring 21, and this latch-bolt normally may be retracted by means of a knob mechanism 22. The lever mechanism is interposed between the latch-bolt 20 and the roll-back on the cylinder lock so that when the locking bolt 7 is in retracted position, the latch bolt 20 75 may be retracted by the cylinder lock means by a person on the outside supplied with a suitable key. In the form shown I employ a lever 23 pivoted at 24 on a locking bolt, a part of the lever being in position to be engaged by the roll-back 18 when the locking bolt is retracted as shown in Fig. 1. A second lever 25 may be pivoted at 21 on the locking bolt, and this lever may engage a suitable abutment on the latch-bolt 20 and be 80 engaged by a part of the lever 23. As will be plain from Fig. 1, rotation of the roll-back 18 in a clockwise direction will serve to retract the latch-bolt 20. Now, if the roll-back 18 be rotated in a counterclockwise direction, as viewed in Fig. 1, the roll-back 85 will engage the tumbler 12 and the locking bolt 7 so as to project the same into the position shown in Fig. 2. Movement of the locking bolt 7 into the projected position thus removes the lever 23 from the path of movement of the roll-back, and of course when the locking bolt is projected the cylinder lock cannot be employed to retract the latch-bolt and, since the locking bolt is in 90 projected position, the door cannot be opened from either the inside or the outside. With the locking bolt in projected position, as shown in Fig. 2, the roll-back may be rotated in a clockwise direction, as viewed in Fig. 2, so as to again actuate the tumbler and retract the locking bolt, provided, of course, the extensible plate 19 is not pro-

jected. Those persons, who may have authority to enter the door when the locking bolt is retracted, are furnished with long keys which, when inserted in the cylinder lock so as to rotate the plug and roll-back, project the plate 19 into the position shown in Fig. 2. If the locking bolt be in retracted position, the projecting plate 19 does not affect the ability of the roll-back to depress 10 the lever 23 and retract the latch-bolt 20 but, when the locking bolt is in projected position, the lever 23 is out of the range of movement of the roll-back and plate 19, and the plate 19, upon rotation of the roll-back 15 in a clockwise direction, will abut some part such as the locking bolt, and the rotation of the roll-back necessary for depressing the tumbler and withdrawing or retracting the locking bolt is thus prevented. It will therefore be seen that a person supplied only with 20 a long key cannot enter the door so long as the locking bolt is projected. Under ordinary conditions with the locking bolt in retracted position, either the long key or the 25 short pass-key may be employed for retracting the latch-bolt.

While the invention has been described in some detail, I do not wish to be strictly limited to the form shown since changes 30 may be made within the scope of the invention as defined in the appended claims.

I claim:

1. In a lock, a lock casing, a locking bolt in said casing, a tumbler carried by said locking bolt, a fixed stump in said casing for gating said tumbler when said locking bolt is in projected and retracted positions, a cylinder lock having a roll-back adapted to coact with said tumbler for ungating the 35 same, and moving said locking bolt to projected and retracted positions, a latch-bolt, lever mechanism carried by said locking bolt and coacting with said latch-bolt for retracting the latter, said tumbler serving to engage said lever mechanism for retracting 40 said latch-bolt when said locking bolt is in retracted position, and an extensible member carried by said roll-back and adapted to abut said locking bolt for preventing rotation of said roll-back sufficient to engage 45 said tumbler for moving said locking bolt when said extensible member is projected.

2. In a lock, a lock casing, a locking bolt therein, a latch-bolt, lever mechanism carried 55 by said locking bolt and adapted to retract said latch-bolt, a cylinder lock having a roll-back thereon for moving said locking bolt to projected and retracted positions, said roll-back serving to engage said lever mechanism 60 for retracting said latch-bolt only when said locking bolt is in retracted position, and

means carried by said roll-back and adapted to contact with a part of said locking bolt when the latter is in projected position, whereby said roll-back is prevented from rotating to retract said locking bolt. 65

3. In a lock, a lock casing, a locking bolt therein, a gated tumbler for holding said locking bolt in projected and retracted positions, a cylinder lock having a roll-back 70 normally adapted to coact with said tumbler and locking bolt for moving the latter to projected and retracted positions, and an extensible member carried by said roll-back and adapted to abut a part of said locking bolt for preventing engagement of 75 said roll-back with said tumbler when said extensible member is projected.

4. In a lock, a lock casing, a locking bolt movable therein, a latch-bolt, a cylinder lock having a roll-back therein for moving said locking bolt to projected and retracted positions, said roll-back serving to retract said latch-bolt when said locking bolt is in retracted position, and means carried by said roll-back and adapted to be projected so as to contact with a part of said locking bolt, when the latter is projected, so as to prevent rotation of said roll-back and thus prevent movement of said latch-bolt and locking 90 bolt by said roll-back.

5. In a lock, a lock casing, a latch-bolt therein, a cylinder lock, a roll-back thereon, means for permitting said roll-back to retract said latch-bolt, extensible means on 95 said roll-back, abutment means within said casing and adapted to be engaged by said extensible means on said roll-back for preventing rotation thereof for retracting said latch-bolt. 100

6. In a lock, a lock casing, a locking bolt movable in said casing, a latch-bolt, lever mechanism to actuate said latch-bolt, a cylinder lock carrying a roll-back adapted to engage said lever mechanism for retracting 105 said latch-bolt when said locking bolt is in retracted position, and extensible means on said roll-back and adapted to abut said locking bolt for preventing rotation of said roll-back, whereby said locking bolt cannot be 110 retracted when said extensible means is in extended position.

7. In a lock, a lock casing, a locking bolt therein, a cylinder lock having a roll-back adapted to move said locking bolt to projected and retracted positions, and an extensible member carried by said roll-back and adapted, when extended, to abut a part in said casing for preventing sufficient rotation of said roll-back to retract said locking bolt. 115 120
